UNITED STATES PATENT OFFICE.

WILLIAM H. FRANKLIN, JR., OF MERRIMAC, MASSACHUSETTS.

GAS-COCK LOCK.

Application filed April 17, 1922. Serial No. 553,520.

To all whom it may concern:

Be it known that I, WILLIAM H. FRANKLIN, Jr., a citizen of the United States, and a resident of Merrimac, in the county of 5 Essex, in the State of Massachusetts, have invented an Improvement in Gas-Cock Locks, of which the following is a specification.

This invention relates to certain improvements in safety controlling or operating means for valves or gas cocks and has for its object, primarily, to provide means whereby when the valve or plug is moved to closed position, it will automatically be come locked, so that it cannot be opened when pushed accidentally, but may be unlocked, by proper manipulation of the operating handles, and opened practically as readily as with any ordinary form of valve 20 of this type which is not provided with a locking means.

Another object of my invention is to provide a construction having the above described characteristics which is simple and durable and may be manufactured at slightly increased expense, as compared with similar devices now on the market and not possessing said characteristics.

I accomplish these objects in the manner hereinafter described and as illustrated in the accompanying drawing in which:—

Fig. 1 is a side elevation of a form of gas cock embodying my invention.

Fig. 2 is a plan view thereof.

Figs. 3 and 4 are sectional views on line 3—4 of Fig. 2, respectively showing the parts in locked and unlocked positions.

Fig. 5 is a plan view, partly in section at line 5 of Fig. 1, showing the cock in partly closed position.

As shown in the drawing, the valve casing *a* has a common form of turning plug *b* therein, such as is commonly used for gas stoves and the like.

According to my invention, a rod *c* is slidably mounted in the head *b'* of the plug, at right angles to the axis thereof and is extended through a handle *d* and connected at its extreme end to the end of the handle, preferably by a screw-thread connection. The handle *d* is slidably mounted on a sleeve *e* therein, said sleeve being rigidly secured to the head *b'* in a recess formed therein. A coiled spring *f* is arranged on the rod *c* within the sleeve between a collar *g*, fixed on the rod *c*, and a plug *h* secured

in the opposite end of the sleeve from that at which it is supported. By this arrangement, the handle *d* may be moved longitudinally on the sleeve and, when drawn outwardly from the head, the spring *f* will be compressed, and will act to return the handle to the normal position in which the handle is engaged with the head. A hemispherical projection *i* is formed integrally with the valve casing and projects in close proximity to the head *b'* with its flat side *i'* next the latter, and a recess *j* is formed in the projection in alignment with the rod *c*, and into which the end of said rod is adapted to be moved when the handle *d* is held in engagement with the head *b'*, which serves as a stop. The end of the rod, which is arranged to enter the recess, is somewhat rounded as shown.

With the above described construction, when the plug is in closed position, the locking rod *c* will be in its normal position, as shown in Fig. 3, so that its end portion will be located in the recess *j* in the projection, one side of the recess thus forming a shoulder for engaging the rod so that the plug cannot be rotated and will be securely locked. When the valve is opened, the handle will first be drawn to the right sufficiently to withdraw the rod *c* from the recess *j*, as shown in Fig. 4. The plug will then be unlocked and free to be turned by its handle to open position. As soon as the cock is unlocked, the handle will be released and will re-engage its stop. When the valve is moved from open to closed position, the end of the rod will engage the surface *i* of the projection by the time the valve is partly closed, so that, during the remainder of the closing movement, said surface will act as a cam face, and will cause the rod to be pressed back, and at the end of this movement the rod will be forced into the recess again by the spring, so that the plug will be locked as before described.

It will be observed that, so far as the closing movement is concerned, the locking means in no way interferes therewith and that the opening movement may be performed with practically the same facility as if the locking means were not present.

I claim—

1. A gas cock comprising a casing having a rotatable stem therein, an arm secured to, and extending from said stem at one side thereof, a handle reciprocally mounted on

- said arm, a locking rod reciprocally movable within said arm, said rod being attached at one end to said handle and being adapted to project beyond said stem at its 5 opposite end, an abutment on said casing arranged to engage one side of said rod to lock the stem in closed position and a spring arranged within the handle to move the handle and rod to locking position.
- 10 2. A gas cock comprising a casing having a rotatable stem therein, an arm secured to, and extending from said stem at one side thereof, a handle reciprocally movable on said arm, a locking rod disposed within the handle and connected thereto at one end and adapted to be extended beyond the opposite side of said stem at its opposite end, an abutment on the casing having a face arranged to engage said extended end of said 15 rod when the stem is in closed position to lock the stem in said position, a spring for holding said rod in locking position, and means including a face on said casing for holding said rod in an inoperative position

as the stem is moved from open to closed 25 position whereby said closing movement is unobstructed.

3. A gas cock comprising a casing having a rotatable stem therein, an arm secured to and extending from said stem at one side 30 thereof, a handle reciprocally movable on said arm, a locking rod slidably mounted within said arm and attached at one end to said handle, and at the opposite end slideable through said stem to project beyond 35 the opposite side thereof, a spring interposed between said arm and rod to hold the rod in projecting position, and a recessed abutment on said casing arranged to receive the end of said rod when the stem is in 40 closed position, and having a face arranged to engage the end of the rod and retract the same as the stem is moved to closed position and to release the rod when in said position.

In testimony whereof, I have signed my 45 name to this specification.

WM. H. FRANKLIN, JR.
